UNITED STATES PATENT OFFICE.

FRANK JOHNSON, OF OAKLEY, CALIFORNIA.

OIL BURNER.

Application filed April 22, 1922. Serial No. 555,978.

To all whom it may concern:

Be it known that I, FRANK JOHNSON, a citizen of the United States, and a resident of Oakley, county of Contra Costa, and State of California, have invented a new and useful Oil Burner, of which the following is a specification.

My invention relates in general to burners for cooking and heating purposes and has reference more particularly to a burner especially adapted for use in burning oil and the object of the same is to produce a cheap, simple and efficient means for utilizing a cheap grade of liquid fuel, such as kerosene, for heating and cooking purposes.

A further object of my invention is to construct the burner in such a manner that the highest degree of heat possible will be obtained from the liquid fuel, and to off-set the danger of using the same due to explosion or other causes usually present in utilizing combustible liquids as a fuel.

My invention is illustrated in the accompanying drawings in which Figure 1 is a view in side elevation and partly in section of the burner and the parts which are used in combination therewith; Figure 2 is a plan view of the burner; Figure 3 is a transverse vertical section through the middle of the burner and Figure 4 is a bottom plan view.

Referring now to the drawing in detail, I wish it to be clearly understood that my burner may be used in various ways, for instance it may be installed in the fire box of a wood or coal cooking range, the fire box of a furnace or other heating stoves, or otherwise set up for use according to requirements. In some instances, of course, certain changes would be required to accommodate the burner to various uses, for instance, sometimes only a single burner, per se, would be required instead of two burners as illustrated in the drawing. The again, more than two burners may be required and the general shape or design of the burner might have to be changed. In all cases, however, the same simple and convenient, practicable principle is employed.

Considering the illustrative embodiment in this light the showing made in the drawing comprises a pan or the like (1) preferably supported by feet or legs (2). The pan comprises a cast metal structure with the feet or legs (2) made as an integral part thereof and with a relatively deep trough

(3) extending continuously around the outer edge of the pan, with exception of the dams (4) and (4') arranged in the trough on opposite sides thereof to provide a support for the pre-heating or vaporizing tube (5) 60 which is supported over the trough (3) with the end (6) thereof threaded into a T (7) having a downwardly presented connection extending through an opening in the dam (4') and made to receive the nipple or the like (8), the threaded end (9) of which is adapted to be connected to the fuel supply pipe which leads from a liquid reservoir not shown.

The ends (6) of the pre-heating or vaporizing tube (5) may be considered as an intake and the end (10) as an outlet, the same having a threaded engagement with a fitting (11) which connects with the manifold pipe (12) cast as an integral part of the flat manifold or distributing plate (13) which is of substantially the same size as the area of the pan surrounded by the trough (3). The manifold pipe (12) is arranged in upstanding relation to the plate (13) and 80 has a cap (14) to close the same with an opening (15) in the cap to admit air. Screwed or otherwise fixed between the fitting (11) and the upstanding manifold pipe (12) is a nozzle (16), the same having 85 a small axial bore (17) establishing communication between the tube (5) and the inside of the manifold pipe (12) through the fitting (11). Produced in the pan (1) concentric with the inside of the manifold pipe 90 (12) is an air opening or intake (18).

The kerosene or other liquid fuel, as the case may be, is supplied by air pressure to the preheating or vaporizing tube (5) as previously mentioned and to start the burner, 95 alcohol or other combustible liquid is poured into the trough (3) to heat the tube (5) and the kerosene distributed therein to vaporize the same so that it is forced through the nozzle (16) into the manifold pipe (12) in 100 a spray and the air entering in the opening (18) making a combustible gas which circulates through the opening (19) in the vertical upstanding part (20) of the casting and back of the manifold pipe (12) where it 105 enters the relatively deep distributing well (21) from where it circulates throughout the space under the plate (13) to the openings (22) and (23) which communicate with the slanting internal openings (24) of the 110

burners, per se. The burners are bolted through their flanges to the top of the plate (13) as best shown in Figure 1, and each comprises a cap (25) having slits (26) around its periphery to leave openings at which point the flame is produced.

One of the important features of my invention resides in the precaution I have taken to prevent the accumulation of combustible gas which might prove disastrous, due to explosion. I therefore arrange a multiplicity of radial slits or cuts (27) around the downwardly presented edge of the plate (13) so as to permit a certain amount of the carbureted charge to escape and the same may be burned at this point to keep the preheating or vaporizing tube (5) hot at all times.

From the above it will be readily seen that I have produced a practical device which is extremely simple to make, convenient to use and requiring only ordinary skill to operate and it might also be added that it will use a minimum amount of kerosene or other liquid fuel, consequently it is cheap to use.

I claim:

1. An oil burner comprising a pan having a trough around its outer edge, a preheating tube supported above said trough, one end of said tube connecting with a liquid fuel supply, a plate mounted on said pan having a base dimension of substantially that of the area of the pan surrounded by said trough, said plate having a downwardly presented outer flange, cuts in said flange extending from adjacent the trough of the pan into the space beneath the plate, an upstanding manifold pipe on said plate, said preheating tube terminating in a fitting connected to an opening in said pipe, a nozzle in said opening through which the fuel is introduced into the manifold pipe from the preheating tube, a manifold distributor on said plate communicating with the manifold pipe; whereby the fuel is distributed throughout the space under the plate, and

burners on the plate communicating with the space under the same substantially as and for the purpose described.

2. An oil burner comprising a pan having a trough around its outer edge, a preheating tube supported above said trough, one end of said tube connecting with a liquid fuel supply, a plate mounted on said pan having a base dimension of substantially that of the area of the pan surrounded by said trough, said plate having a downwardly presented outer flange, cuts in said flange extending from adjacent the trough of the pan into the space beneath the plate, an upstanding manifold pipe on said plate, said preheating tube terminating in a fitting connected to an opening in said pipe, a nozzle in said opening through which the fuel is introduced into the manifold pipe from the preheating tube, a manifold distributor on said plate communicating with the manifold pipe; whereby the fuel is distributed throughout the space under the plate and burners on the plate communicating with the space under the same, said plate including the manifold pipe, the manifold distributor, and the outer downwardly presented flange on the edge of the plate, being cast as an integral one piece structure.

3. An oil burner, including a pan with a trough around the edge thereof, a plate on said pan with a space between the plate and pan, burners communicating with said space, and a multiplicity of small cuts communicating between said space and the edge of the said trough, a preheating tube supported over said trough, one end of said tube connected to a source of liquid fuel supply and the other end communicating with the space between the plate and pan.

4. An oil burner as set forth in claim 3 and in which the plate and pan are separate castings, and in which the burners are made separate from the plate to which they are mounted.

FRANK JOHNSON.
